(57) **CLAIM**

The ornamental design for a rail cover panel with surface texture, as shown and described.

DESCRIPTION

FIG. 1 is a front, top, right perspective view of a rail cover panel with surface texture attached to a firearm showing our new design with surface texture shown schematically;

FIG. 2 is a front, top, left perspective view of the rail cover panel with surface texture of FIG. 1 with the firearm omitted; FIG. 3 is a right side elevation view of the rail cover panel with surface texture of FIG. 1 with the firearm omitted, the left side elevation view being a mirror image thereof;

FIG. 4 is a rear elevation view of the rail cover panel with surface texture of FIG. 1 with the firearm omitted, the front elevation view being a mirror image thereof;

FIG. 5 is a top view of the rail cover panel with surface texture of FIG. 1 with the firearm omitted;

FIG. 6 is a bottom plan view of the rail cover panel with surface texture of FIG. 1 with the firearm omitted;

FIG. 7 is a front, bottom, left side perspective view of the rail cover panel with surface texture of FIG. 1 with the firearm omitted; and,

FIG. 8 is a perspective view of the surface texture of FIG. 1 shown enlarged.

The broken lines showing portions of the design in all figures is included for the purpose of illustrating environment and unclaimed features and forms not part of the claimed design. The relative density and proportions of the surface treatment is accurately illustrated in FIG. 5. For practicality FIGS. 1, 2 and 3 show token representations of the surface treatment. The texture pattern sample illustrated in FIG. 8 is applied uniformly within the area circumscribed for the texture.
